UNITED STATES PATENT OFFICE.

JULIUS SCHUMACHER, OF UNION CITY, NEW JERSEY, ASSIGNOR TO THE SCHWARZEN-BACH COMPANY, OF UNION CITY, NEW JERSEY, A CORPORATION OF NEW JERSEY.

SHUTTLE SPINDLE.

Application filed March 16, 1926. Serial No. 95,092.

This invention relates to shuttles for looms and has for an object to provide an improved construction wherein the spindle acts to hold in an efficient manner the cop core in place.

Another object of the invention is to provide a spindle structure for shuttles wherein an expanding and contracting member is provided to grip and release the cop core.

10 A still further object, more specifically, is to provide a spindle structure for shuttles wherein the spindle may function in the usual manner but continually presents an expanding and contracting member positioned to be contracted when the spindle is moved to an outer position and expanded when moved to an inner position whereby the cop of the core is gripped when the spindle is in operating position.

20 In the accompanying drawing—

Figure 1 is a plan view of a shuttle with the spindle embodying the invention applied thereto.

25 Figure 2 is a sectional view through Figure 1, approximately on line 2—2.

Figure 3 is a fragmentary view showing one end of the shuttle illustrated in Figure 1 and illustrating how the spindle may be swung to an open position and the cop core 30 holding device constricted.

Figure 4 is a side view of a spindle showing a modified form of the invention.

Figure 5 is a plan view of one end of a shuttle with another form of the invention applied thereto.

Figure 6 is a sectional view through Figure 5, approximately on line 6—6.

Figure 7 is a fragmentary transverse sectional view through Figure 6 on line 7—7, the same being on an enlarged scale.

Figure 8 is an enlarged fragmentary top plan view of a cop core holding member embodying certain features of the invention.

Referring to the accompanying drawing by numerals, 1 indicates the usual shuttle which is provided with a specially constructed spindle 2 for receiving the cop core 3. The spindle 2 is formed with an opening 4 in the usual manner and is provided specially with a stop 5 which may be screw threaded into part of the spindle as illustrated in Figure 2. A stop 6 of any desired kind, as for instance, a pin, is provided at the inner end of the spindle. The spindle 2 is pivotally mounted in the usual way and is held in its outer or inner position by a spring 7 in the usual manner.

Difficulty has been had in the past to maintain the core 3 properly on the spindle 2 and various means have been tried to obviate the slipping of this core. In the present invention, means have been provided for firmly locking the core in position for permitting a quick and easy removal. This means includes a member 8 which preferably tapers for its full length and is provided with an external thread and with two slots 9 extending from near the head 10 of the spindle 2 to near the stop 5 as illustrated in Figure 2. This tubular tapering threaded member is slipped over the small end of the spindle 2 and by reason of the opening 4, the spindle collapses enough to permit the device 8 to slip over the stop 5 until the parts are positioned as shown in Figure 2. It will be noted that when the parts have been positioned in this manner, member 8 cannot accidentally move off the spindle and by reason of the pin 6 fitting into one of the slots 9, the device 8 cannot rotate. It will be noted that the slots 9 are arranged on top and beneath the spindle so that when the spindle is swung to an open position as shown in Figure 3 and in dotted lines in Figure 2, the inner or large end of member 8 engages the arms 11 and 12 of plate 13. As these arms are spaced a less distance apart than the large end of member 8, said large end will be forced together by a cam action as the spindle is moved to an open position. This will cause member 8 to be contracted from the position shown in Figure 1 to the closed position shown in Figure 3. When the parts are in the position shown in Figure 3, core 3 is slid over the spindle and screwed down on the locking or holding member 8 as far as the fingers of the operator can do so conveniently. The spindle, together with the core 3 and the cop thereon, are all then swung back to the position shown in Figure 1 and as soon as this position is taken, member 8 will expand so as to press the threaded portion against or into the core 3, for firmly gripping or locking the same in place. The cop is, therefore, locked against accidental dislodgment and the shuttle may be used in the usual manner until the cop is entirely unwound whereupon the spindle may be moved to the position shown in Figure 3 and core 3 removed, after which a new cop may

be applied as above described. It is to be noted that the member 8 is tubular and tapers, said tubular structure causing the lower end to act as cams in connection with 5 the arms 11 and 12 whereby the slots 9 are readily closed automatically as the spindle 2 is swung to its open position.

In Figure 4, a modified structure is shown wherein the lug 6' is preferably formed integrally with the head 10 and the substantially annular depression 14 is provided in spindle 2 at a point similar to the point occupied by the stop 5. The ring 15 is fitted into the depression 14 and acts as a stop for member 8 15 when the modified form of spindle shown in Figure 4 is in use. When this form of the invention is used, the ring 15 is preferably applied after member 8 has been placed in position.

Figures 5 to 8 inclusive disclose a further form of the invention wherein the pin and ring on the spindles 2 are eliminated and, consequently, the spindles are not weakened in any manner. In this form of the invention, the holding member 16 is provided with a spiral raised portion 17 and with notches 18 and 19 whereby the end is formed into projections 20 and 21 at one point, said projections being adapted to fit partly 25 around the bent down or depending portion 22 of the stop 23. The stop 23 may be of any desired material, as for instance, a round bar fitted into the member 24 and extending therefrom as shown in Figure 6 30 with the end 22 bent down and projecting through the opening provided by notches 18 and 19. The holder 16 is formed to normally assume the position shown in Figures 5 and 8 with the slit 25 open. However, 35 when the parts open as just described, ends 20 and 21 will still overlap the depending portion or end 22 and, consequently, holder 16 cannot be removed. When it is desired to remove the holder 16, a screw driver or 40 other instrument is inserted into slit 25 and the parts spread to a greater extent or until the ends 20 and 21 may pass the end 22 of stop 23. It will be noted that the holder 16 is freely slideable on the spindle 2 but is held 45 against sliding movement by the ends 20 and 21 and also is prevented from independent rotation as the depending end portion 22 will strike the holder 16 in the notches 18 and 19.

When it is desired to remove the core 3, the parts are raised from the position shown in Figure 5 until the arms 11 and 12 strike the outside surface of the large end of 50 holder 16 and act as cams for forcing the slit 15 closed. It will be noted that the arms 11 and 12 engage the holder 16 substantially 55 at points 26 and 27 and substantially close

the slit 25 whereby the core 3 may be easily applied or removed. It will be noted that the windings 17 are comparatively steep 65 whereby the core 3 may be quickly screwed in place or unscrewed without any appreciable force but when the parts are moved back to the position in Figure 5, the core is gripped firmly by reason of the spreading 70 automatically of the holder 16.

What I claim is:

1. A shuttle, comprising a body of substantially usual structure, a plate formed with a pair of arms acting as cams, a spindle pivotally mounted in the body and swingable so that it may be swung to a position extending between said arms, and a collapsible and distensible cop holding member mounted on the spindle and positioned with one end near the pivotal end of the spindle and positioned to be engaged by said arms and constricted thereby when the spindle is moved to an outer position.

2. In a loom a spindle, a cop holding device mounted on the spindle, said cop holding device being formed with a slot merging into notches, and a hook carried by the spindle formed with a depending portion projecting into said notches and interlocking 90 somewhat with the holding device whereby the hook prevents the independent rotation of the cop holding device and independent longitudinal movement thereof.

3. A shuttle comprising a body of substantially the usual structure, a plate formed with a pair of arms acting as cams, a spindle pivotally mounted in the body and swingable so that it may be swung to a position extending between said arms, a collapsible and distensible cop holding member mounted on the spindle and positioned with one end near the pivotal end of the spindle and positioned to be engaged by said arms and constricted thereby when the spindle is moved to an outer position, said cop holding member being formed with a notch, and a hook connected to said spindle with one end projecting into said notch for locking the cop holding member against rotation.

4. In a loom shuttle a spindle, a cop holding device mounted on the spindle and split from near the pivotal point of the spindle to near the opposite end of the holding device, said holding device also being provided with facing notches merging into the split portion, means associated with the spindle for contracting the cop holding device when the spindle has been moved to an outer position, and a hook carried by the spindle formed with an extension projecting into said notch.

JULIUS SCHUMACHER.
